UNITED STATES PATENT OFFICE

111,143

DESIGN FOR A CARBONATED WATER BOTTLE FILLER

Robert J. Helberg, Seattle, Wash., assignor to Sy-
fil Corporation, Seattle, Wash., a corporation
of Washington

Application March 9, 1938, Serial No. 75,705

Term of patent 7 years

To all whom it may concern:

Be it known that I, Robert J. Helberg, a citizen of the United States, residing at Seattle, in the county of King and State of Washington, have invented a new, original, and ornamental Design for Carbonated Water Bottle Fillers, of which the following is a specification, reference being had to the accompanying drawings, forming part thereof.

Figure 1 is a side elevation of a carbonated water bottle filler, showing my new design.

Figure 2 is a side elevation of the same from the opposite side, but with parts in a different position.

Figure 3 is a side elevation of the article as seen in Figure 2, the viewpoint being at 90° to the latter figure.

I claim:

The ornamental design for a carbonated water bottle filler, as shown.

ROBERT J. HELBERG.
